UNITED STATES PATENT OFFICE.

JOHN S. GULLBORG, OF CHICAGO, ILLINOIS, ASSIGNOR, BY MESNE ASSIGNMENTS, TO THE ROTARY KING SAFETY RAZOR COMPANY, OF NEW YORK, N. Y., A CORPORATION OF DELAWARE.

SAFETY RAZOR.

1,417,988.

Specification of Letters Patent. Patented May 30, 1922.

Application filed March 6, 1920. Serial No. 363,650.

To all whom it may concern:

Be it known that I, JOHN S. GULLBORG, a citizen of the United States, residing at Chicago, in the county of Cook and State of

Illinois, have invented a certain new and useful Improvement in Safety Razors, of which the following is a full, clear, concise, and exact description, reference being had to the accompanying drawings, forming a 10 part of this specification.

This invention relates to improvements in razors and more particularly relates to those commonly known as safety razors.

The primary aim of the device of my invention is to impart to the blade a shearing property or function while in use, and to accomplish this by a simple and economic structure, capable of quick and facile assembly and disassembly.

Another object of my invention is to provide an improved and efficient blade for use with the razor, together with means on the razor specially suited to engage the blade and impart thereto the necessary motion aiding in the performance of the cutting function by the blade.

I accomplish the above objects by the provision of a friction roller mounted at a convenient point on the head of the razor and adapted to engage the face of the user while the razor is in use; a suitable lever receiving motion of the roller through a cam groove in the intermediate portion thereof, the lever being in engagement with the blade, which latter is detachably mounted for reciprocation angularly relative to the direction of motion of the razor over the face of the user, whereby a shearing action is imparted to the blade which greatly enhances the cutting possibilities of the same, lengthens the life of the blade and avoids tearing the hair or abrading the skin of the user.

I attach considerable importance to the blade and its connection to the lever mechanism for reciprocating the blade, although it will be appreciated that minor changes may be required and made in the matter of adjustment, size, shape of lever and notch

in the blade without materially departing 50 from the essence of the invention.

A more concrete conception of a preferred form of my invention may be gathered from the following description of the details of construction and the claims, taken 55 in connection with the accompanying drawing, in which:

Figure 1 is a side elevation of a safety 60 razor embodying the improvements of my invention;

Figure 2 is a front elevation of the same;

Figure 3 is a section taken on the line 3—3 of Figure 2, looking in the direction of the arrow;

Figure 4 is a longitudinal section taken 65 on the line 4—4 of Figure 1;

Figure 5 is a similar view taken on the line 5—5 of Figure 1, and

Figure 6 is a perspective view of the blade 70 which is employed.

Referring in detail to the preferred embodiment of my invention, 10 designates the head portion of the razor, said head being formed with an intermediate offset portion 11, provided with a threaded opening to receive the threaded shank 12 of a handle 13, the handle being provided with a plurality of knurled portions 14.

The head portion or frame 10 is bent 75 downwardly to form an angular portion 15 forming a blade support, the free margin of the blade support 15 being provided with a plurality of tongues 16 which project slightly beyond the cutting edge 17 of the blade 18 to form a guard.

The blade 18 is provided with a pair of slots 19 in alignment with the longitudinal axis of the blade and the rear edge 20 of the blade is provided with a notch 21 for a purpose which will hereinafter appear. The 80 blade is adapted to rest upon the support 15 and is guided by a pair of pins or rivets 22 carried by the support and arranged in alignment with the longitudinal axis thereof. The pins are provided with enlarged head portions 23 which engage in the slots 19 and said head portions 23 are of slightly greater thickness 85 90 95

than the thickness of the blade so as to maintain the blade retainer 24 slightly in spaced relation to the blade and at the same time to permit the retainer to maintain the 5 blade in operative position.

The outer edge of the blade retainer 24 is beveled to expose the cutting edge of the blade 18 and is provided with lugs 25 at its inner opposite corners, said lugs being twisted 10 as at 26 into vertical alignment and provided with openings 27 to receive bearing screws 28, said bearing screws engaging in upturned lugs 29 formed on the opposite end of the head 10 of the razor. The inner 15 ends of the screws 28 are provided with bearing portions 30, which engage in complementary openings in the ends of a roller 31. The member 24 is adapted to be swung upwardly to expose the blade and to permit 20 such movement. The free end edges of the retainer are provided with finger pieces 32 for this purpose. The lugs 25 are provided with cam portions 33 which engage the free 25 ends of spring tongues 34 formed on a plate 35 secured to the under face of the blade support 15 by means of a screw 36.

The roller 31 is knurled as at 37 on its peripheral surface and is provided intermediate its ends with a sinuated peripheral 30 groove 38, adapted to receive a pin 39 carried by a lever 40 pivoted at 41 to the head 10 of the razor. The free outer end of the lever 40 is adapted to engage, as shown in Figure 3, in the notch 21 formed in the inner 35 non-cutting edge of the blade 18.

In use, the retainer 24 is raised by means of the lug 32 clear of the support 15. A blade similar to the blade 18 is placed upon the support with the slots 19 therein engaging 40 the heads 23 of the pins 22 and with the notch 21 in engagement with the free end of the lever 40. The retainer is then moved back to the original position and the razor is ready for use. As the razor is 45 drawn over the face of the user the roller 31 contacts therewith and rotative movement is imparted to said roller. Rotative movement of the roller imparts oscillating movement to the lever 40 which in turn reciprocates the blade transversely of the direction 50 of movement of the razor over the user's face. Thus a shearing action is obtained which, as pointed out hereinbefore, improves both the efficiency of the razor and speed 55 with which the same may be used. The retainer 24 does not materially hinder the reciprocation of the blade, but the space permitted by the head 23 of the pins 22 is sufficient to prevent the blade from jumping off 60 the pins.

In the foregoing description of structural details, I disclose a preferred embodiment of my invention, and while not limiting the same to the exact details as enumerated, except in so far as the scope of the claims is

concerned, I lay particular stress upon the blade structure and its relation to the particular type of actuating means therefor, especially as concerns the location of the application of motion of the blade.

I claim:

1. A razor comprising a frame, a blade having a notch in the intermediate portion of the rear edge thereof, said blade being 70 slidable transversely on said frame, a roller mounted above and to the rear of the blade, an oscillating lever below the roller and to the rear of the blade and having its free end engaged with said notch, and means on said lever engageable with the roller for receiving motion from said roller.

2. A razor comprising a frame, a blade slidable transversely on said frame and having a notch in the intermediate portion of the rear edge thereof, a roller mounted on 85 said frame above and to the rear of said blade, an oscillating lever having its free end engaged in said notch, said roller having a sinuated groove, and a pin on said lever engaging in said groove.

3. In combination, a razor comprising a frame, a blade for reciprocation on said frame, means on the frame engaging the blade only at its intermediate portion, and comprising a lever, a roller above and to the 90 rear of said blade for engagement with said lever, bearings for said roller, a blade retainer, said retainer being pivoted co-incidental with the bearings of said roller and adapted to swing down over the blade when 100 in use.

4. In combination, a razor comprising a frame, a blade for reciprocation on said frame, means on the frame engaging the blade only at its intermediate portion, and comprising a lever, a roller above and to the rear of said blade for engagement with said lever, bearings for said roller, a blade retainer, said retainer being pivoted co-incidental with the bearings of said roller and 105 adapted to swing down over the blade when in use, said retainer having cam portions, and spring means carried by said frame to engage said cam portions for retaining said retainer in the protecting position.

5. A razor comprising a frame, a blade mounted for reciprocation on said frame and having a notch in the rear edge thereof, a roller mounted on said frame to the rear and above said blade, removable bearings for 110 said roller, and a blade retainer adapted to extend over said blade and pivoted on said bearings and means engaging in the notch in said blade for imparting movement thereto.

6. In combination, a razor comprising a 125 frame, a blade mounted for reciprocation on the frame, said blade having a notch in its rear edge, a lever pivoted on said head and having its free end engaging the notch in said blade, a roller mounted on the frame 130

and having a sinuated groove therein, said lever having a portion intermediate its ends engaging in said groove, and means for guiding the blade on said head.

5 7. In combination, a razor comprising a frame, a blade mounted for reciprocation on the frame, said blade having a notch in its rear edge, a lever pivoted on said head and having its free end engaging the notch in
10 said blade, a roller on the frame having a

sinuated groove, said lever having a portion intermediate its ends engaging in said groove, a pair of pins on said head for engaging said blade to guide the same, and a retainer abutting said pins to prevent dislodgement of the blade. 15

In witness whereof, I hereunto subscribe my name this 3rd day of March, 1920.

JOHN S. GULLBORG.
